UNITED STATES PATENT OFFICE.

SIMON D. ALTER AND LEWIS T. YOUNG, OF PHILADELPHIA,
PENNSYLVANIA.

FLASH-LIGHT APPARATUS.

SPECIFICATION forming part of Letters Patent No. 625,133, dated May 16, 1899.

Application filed December 21, 1898. Serial No. 699,936. (No model.)

To all whom it may concern:

Be it known that we, SIMON D. ALTER and LEWIS T. YOUNG, citizens of the United States, and residents of Philadelphia, Pennsylvania, have invented certain Improvements in Flash-Light Apparatus, of which the following is a specification.

Our invention consists of a modified form of the flash-light apparatus for which we obtained Letters Patent No. 613,955, dated November 8, 1898, the object of our present invention being to provide for the explosion of the flash-powder without the necessity of locating the mass of powder at a point more or less remote from said igniting device, our present invention enabling us to locate the igniting device directly in the midst of a mass of the powder. Hence we are enabled to provide cartridges of flash-powder each containing an electric igniter.

In the accompanying drawings, Figure 1 is a sectional view of a flash-powder cartridge with an electric igniter constructed in accordance with our invention. Fig. 2 is a top view of the same, partly in section; and Figs. 3 and 4 are views illustrating the application of our present invention to flash-light apparatus of the character shown in our former patent.

It is practically impossible to explode ordinary flash-powder by means of an electric igniter if the powder is brought into direct contact with said igniter, because the metallic powder provides a conductor between the terminals of the igniting device, and thus robs the igniter of current to such an extent that in case of an incandescing igniter the platinum wire is not heated to such an extent as to cause an explosion and in the case of a sparking-igniter there is not sufficient current to form a spark. Furthermore, if the igniting device was such as to explode the powder the heat and concussion caused by the explosion would destroy the igniter. In our former patent, therefore, we placed the powder at a point more or less remote from the igniter and connected the two by means of a fuse. It is advisable in some cases, however—as, for instance, in a prepared cartridge—to place the igniter in the midst of the mass of powder.

In carrying out our present invention, therefore, we envelop the metallic portions of the igniter in a covering of inflammable insulating material, on which the powder is deposited, so that the igniter first sets fire to the inflammable insulating material and the latter fires the charge of powder. By this means the metallic powder does not come into contact with the igniting device, so as to rob the same of current. Consequently a current of limited power is sufficient to cause incandescence or sparking of the igniter, and the cushion of gases arising from the combustion of the inflammable insulating material interposed between the igniter and the flash-powder serves to prevent the destruction of the igniter by the heat and concussion caused by the explosion of the flash-powder.

In Figs. 1 and 2 of the drawings, 1 represents a box or case provided with a suitable lid or cover 2 and containing a mass of flash-powder 3, an incandescing igniter 4, and a mass of inflammable insulating material 5, interposed between the latter and the flash-powder. In this case the incandescing igniter is a simple platinum wire soldered to the exposed terminals of the electric conductor, which are carried into the interior of the box, any desired means being employed for causing a current to flow through the conductor, so as to render the wire 4 incandescent.

The inflammable insulating material employed may be ordinary guncotton, paper, or other material which can be readily set on fire by the heat of the incandescent wire, but which will offer a resistance greater than that of the wire to the passage of the electric current from one terminal of the igniter to the other. A cartridge of this character may be loaded and fired a number of times in succession, care being taken on each reloading to so cover the exposed metallic portions of the igniting device as to prevent the access of the flash-powder thereto in such manner as to form an electric conductor between the terminals independently of the platinum wire, or, on the other hand, the connection 4 may be fused on each passage of the current and replaced if it is desired to again use the cartridge.

In applying our invention to the flash-light apparatus shown in our former patent we may, when the incandescent igniting device is used, adopt the construction shown in Fig. 3, in which the platinum wire 13 is soldered directly to the ends of the conducting-wires and passes through openings in the partition 12 of the box and through like openings in a strip or disk 25 of asbestos-paper or other heat-resisting insulating material interposed between said partition and the metallic plate 14 thereon. In this case the exposed portion of the platinum wire 13 is first covered with the inflammable insulating material 5 and the flash-powder is then poured upon the latter. In like manner, when a sparking device is used instead of an incandescent igniter the terminals 16 and 17 of the sparking device are first covered with insulating material 5 and the powder is piled upon the latter, as shown in Fig. 4.

Having thus described our invention, we claim and desire to secure by Letters Patent—

25 1. The mode herein described of igniting flash-powder by an electric current, said mode consisting in first covering the exposed metallic portions of the igniting device with insulating material susceptible of being inflamed by the passage of the current through the igniter, then applying the flash-powder to said inflammable insulating material so that it is prevented by the latter from coming into

contact with the metallic portions of the igniter, and then passing a current through the igniter whereby the inflammable insulating material is first fired and in turn fires the flash-powder, substantially as specified. 35

2. A flash-light apparatus in which are combined a mass of flash-powder, an electric igniting device embedded therein, and insulating material interposed between the igniting device and the flash-powder and susceptible of being inflamed by the passage of the current through the igniter, said insulating material preventing the direct access of the flash-powder to the igniting device, and serving, when inflamed, to fire said flash-powder, substantially as specified. 40 45

3. A flash-light cartridge consisting of a box or casing containing a mass of flash-powder, and having embedded in the latter an electric igniting device covered by insulating material susceptible of being inflamed by the passage of the current through the igniter, and serving, when thus inflamed, to fire the flash-powder, substantially as specified. 50 55

In testimony whereof we have signed our names to this specification in the presence of two subscribing witnesses.
